BASE FOR FREESTANDING FIREPLACE

Wendell H. Lovett, 14445 SE. 55th St.,
Bellevue, Wash. 98004

Filed Jan. 29, 1965, Ser. No. 83,631

Term of patent 14 years

(Cl. D81—7)

FIG____ 1

I claim:

The ornamental design for a base for freestanding fireplace, as shown and described.
